FREEZING TRAY

Arthur J. Frei, Sr., Dayton, Ohio, assignor to
 General Motors Corporation, Detroit, Mich., a
 corporation of Delaware

Application August 31, 1950, Serial No. 182,499

7 Claims. (Cl. 62—108.5)

1

This invention relates to mechanically-ejecting freezing trays suitable for use in household refrigerators.

An object of this invention is to provide an improved form of mechanically operated freezing tray from which dry hard frozen ice blocks may be harvested without the necessity of any application of heat thereto.

Some features of the partitioning grid of this invention are: its ease of operation due to the hand lever camming directly upon the endmost cross wall with an initial enormously multiplied force to initiate the loosening operation by loosening the first transverse row of ice blocks, after which the loosening of additional ice blocks requires much less force; the longitudinal actuating bar or bars for successively moving the remaining cross walls forward are directly moved forward by their engagement with the endmost cross wall and are thereafter positively restored to their initial or freezing position by direct action of the hand lever itself; the endmost cross wall is restored to its initial or freezing position directly by the restoring movement of said actuating bar or bars.

By incorporating the above features in a three-row grid having two longitudinally extending partitions and any desired number of cross partitions (usually five or six cross partitions), a very simple efficient and easily operated design of a three-row grid is provided. Additional features specific to a three-row grid made according to this invention are: the two longitudinal partitions are inclined outwardly toward their bottom portions to permit the central ice blocks to more readily be removed after being loosened by the forward swinging movement of the cross walls; the single hand lever is pivotally mounted upon both of the two longitudinal partitions and thus retains them in effective lateral alignment and thereby retains all the cross partitions substantially in their normal directly transverse positions when viewed in plan; the hand lever cams directly against the endmost cross wall at two materially separated areas and thus prevents excessive camming pressure upon said endmost cross wall and provides a more efficient camming action thereupon.

Further objects and advantages of the present invention will be apparent from the following description, reference being had to the accompanying drawings wherein a preferred embodiment of the present invention is clearly shown.

In the drawings:

Fig. 1 is a plan view of the grid and pan of this invention, all the parts being shown in freezing position.

2

Fig. 2 is a section on line 2—2 of Fig. 1, but shows the forward endmost cross wall having been tilted forward slightly to loosen the first three ice blocks from both pan and grid by the upward swinging of the hand lever to the position shown.

Fig. 3 is an end view of the grid showing the parts in freezing position, but with the endmost forward cross wall removed in order to more clearly show the parts immediately therewith.

Fig. 4 is a detail side view of one of the longitudinal partitions, and Fig. 5 is an edge view thereof.

Fig. 6 is a side view of one of the actuating bars, and Fig. 7 is one edge view thereof.

Fig. 8 is a detail face view of one of the cross partitions and Fig. 9 is an edge view thereof.

Figs. 10, 11 and 12 are detail views of the hand lever, Fig. 10 being a top view, Fig. 11 is a side view, and Fig. 12 an end view thereof.

Similar reference characters refer to similar parts throughout the several views.

10 designates the container pan, which is preferably drawn in one piece from sheet aluminum alloy and has a flat bottom wall 11, slightly outwardly inclined side walls 12, and end walls 13 outwardly inclined at a greater angle so that the first three ice blocks to be loosened by the grid mechanism (as herein described) will easily slide upwardly along the inclined end wall 13 when the endmost cross wall is swung forward.

The removable grid 20 has two longitudinal partition walls 21, preferably diverging apart slightly from top and bottom and each having an outline shaped to fit loosely within pan 10. Along the top edge of each longitudinal wall 21 a relatively narrow actuating bar 22 is arranged to slide longitudinally back and forth upon operation of the grid as later described herein. A series of cross partition walls 25 are loosely mounted upon said longitudinal walls 21 at their lower edges, and upon the actuating bars 22 adjacent their upper edges in such manner that said cross walls 25 may be swung forwardly and rearwardly relative to the stationary longitudinal walls 21 when actuating bars 22 move longitudinally back and forth.

Cross walls 25 each have two inclined slots 26 therein thru which longitudinal walls 21 loosely extend, and two vertical slots 27 (forming an extension of slots 26) thru which the actuating bars 22 loosely extend (see Fig. 8). The two longitudinal walls 21 have a series of notches 28 cut in their lower edges to loosely receive the small laterally projecting tongues 29 at the bottom margins of cross walls 25 as shown in Fig. 8. The two actuating bars 22 have open notches

30 suitably spaced along the upper edges thereof to loosely receive the continuous portions 31 of cross walls 25 lying above slots 28 therein.

Cross walls 25 may be assembled upon longitudinal walls 21 and actuating bars 22 as follows. The two longitudinal walls 21 and their overlying bars 22 are held in a suitable fixture with each of the notches 30 in the actuating bars 22 held approximately directly opposite its corresponding notch 28 in the longitudinal walls 21. Then each cross wall 25 is slightly sprung sufficiently to move the small tongues 29 thereon out of alignment with the slots 26, whereupon each cross wall can then be slipped down over bars 22 and longitudinal walls 21, which can then readily enter their slots 27 and 26 respectively. As each cross wall is so passed down it finally reaches a position where its two continuous portions 31 lie within their corresponding notches 30 in the two actuating bars 22, at which position the small tongues 29 will register with their lower notches 28 and will enter same when the cross wall is released and can return to its normal unsprung position. Or the following similar method may be used for assembling these parts: the cross walls 25 may be held spaced apart and upside down in a suitable fixture with each wall 25 held sprung so that the small tongues 29 do not obstruct the entrance of the actuating bars 22 and longitudinal walls 21 into slots 26. Then bars 22 are passed thru the then open bottom ends of slots 26 into their slots 27 with their notches 30 registering with the continuous portions 31 of the cross walls 25. Next the longitudinal walls 21 are similarly passed thru slots 26 into final position with their lower notches 28 lying in approximate registration with the small tongues 29. Thereupon cross walls 25 are released and permitted to spring back to normal shape (in a single plane) and when so released the tongues 29 will snap into their corresponding notches 28. Then these parts will be loosely assembled together and the actuating bars 22 can be slid to and fro along the upper edge of walls 21 to cause cross walls 25 to swing about their bottom edges as a hinge axis to inclined positions either side of a vertical position.

The forked hand lever 40 has two opposed outwardly projecting journal pins 41 which pivot in the aligned holes 42 located in the upper margin of the two longitudinal walls 21. The two forked legs 43 of lever 40 can be sprung toward each other sufficiently to permit the two opposed journal pins 41 to pass down between the two longitudinal walls 21 (in the partition assembly described above) into registration with the aligned holes 42, after which the legs 43 are permitted to spring apart back to normal position and cause pins 41 to project into their pivot holes 42.

Lever 40 has a rounded cam surface 45 on each of its two legs 43, which two cams 45 directly engage the forward endmost cross wall 25 when said cross wall is in its rearwardly inclined freezing position. Due to the close proximity of pivot pins 41 to the surface of cross wall 25 against which cams 45 first begin to act during the ice-loosening operation, the mechanical advantage practically obtainable by such a cam arrangement can be made enormous or moderate simply by designing the curvature of cam surface 45 accordingly. Preferably cam surfaces 45 are given such a curvature that when hand lever 40 is swung upwardly said cams 45

engage two areas on the rear surface of the endmost cross wall 25 and at first push same forward relatively very slowly but with a very high mechanical advantage (ratio of the force of cams 45 against cross wall 25 to the force applied by hand on lever 40). After the engaged portions of the endmost cross wall 25 are so pushed and flexed forward only a few thousandths of an inch by cams 45 the entire cross wall will become peeled loose from the ice in which it is embedded. As lever 40 is swung further upwardly at a uniform rate cams 45 are designed to push said cross wall forward with a progressively reduced mechanical advantage and hence provide greater travel to the cross wall to entirely loosen the endmost three ice blocks from both the grid and pan and thereafter cause said blocks to slide upwardly along the inclined end wall 13 of the pan. Preferably the front face of cams 45 are so constructed as to allow slight free movement of the handle before it engages the cross wall to operate the grid.

When said endmost cross wall 25 is in freezing position the forward surfaces of its two continuous portions 31 lie to the rear of the bottom forward edge 51 of notch 30 in actuating bar 22 by a small clearance 50. This small clearance 50 permits endmost cross wall 25 to swing forward sufficiently to loosen the endmost three ice blocks (as described above) before said cross wall engages said forward edge 51 of notch 30, hence only the endmost cross wall 25 is moved by lever 40 until after said first three ice blocks are loose. Thereafter endmost cross wall 25 engages said forward edges 51 and so pulls the two actuating bars 22 forward upon further upward swinging of hand lever 40. Fig. 2 shows the parts in position with the endmost cross wall 25 having been swung forward thru a very small angle to loosen the first three ice blocks and take up the lost motion due to clearance 50. Now when said two actuating bars 22 are pulled forward by endmost cross wall 25 the notches 30, progressively wider from front to rear in said bars 22, successively engage and swing forward the remaining cross walls 25, one after the other, from the front to the rear of the grid and so successively loosen from the pan and grid groups of three ice blocks at a time. It will be noted that the cams 45 can be easily and simply shaped to give an ample total travel to actuating bars 22 to complete the desired full swing of the last cross wall 25 to be moved. By progressively increasing the radius of curvature of cams 45 outwardly from the pivot center 41 a total travel of bars 22 of over three-quarters of an inch can readily be had in a 10 inch length grid. Thus it is seen that this cam arrangement not only provides a highly desirable very large mechanical advantage for initiating the loosening of the ice blocks (since the first ice blocks are the most difficult to loosen), but also provides a desirable large total travel of the actuating bars 22 such as will swing all of the cross walls thru a large angle and so more completely free the ice blocks from the grid. In Fig. 2 the cross walls 25 are shown inclined rearwardly at an angle of about 17 degrees from the vertical when in freezing position. The cams 45 here shown will easily give such total travel to actuating bars 22 as will swing all the cross walls thru a vertical position and to a forwardly inclined position of 17 degrees, or more if so desired, thus completely freeing all the ice blocks from both pan and grid. Then the grid may

be simply lifted by handle 40 up from the pan leaving all the loosened ice blocks in the pan. Only a few of all of the ice blocks may be removed at one time simply by stopping the swinging movement of lever 40 whenever desired. Each cross wall 25 except the rearmost normally swings about its lowermost edge as a pivot axis. The rearmost notch 28' in each longitudinal wall 21 is shaped as clearly shown in Figs. 2 and 4 so that the rearmost cross wall 25 swings about the forward upper edges of the two notches 28' (i. e. points A) as a pivot axis. The purpose of this is to cause the lower portion of said rearmost cross wall when swung forward to kick backwards and so insure the loosening from the grid of the last three ice blocks.

To restore the grid parts to freezing position, hand lever 40 is swung clockwise (as viewed in Fig. 2). Each actuating bar 22 has a laterally turned ear 60 projecting into the path of said lever 40 so that said ears 60 engage the rear surfaces of said lever (immediately opposite cam portions 45 thereon) and are cammed backward thereby. Upon lever 40 reaching its down or horizontal position shown in Fig. 1 the two actuating bars 22 will be held thereby in their rearmost or freezing position. As said bars 22 move rearward the forward edges of notches 30 therein swing the cross walls 25 rearwardly until all except the front cross wall abut against the small lateral ears 65 on longitudinal walls 21 which serve as stops therefor. Thus all cross walls except the forwardmost cross wall are positively retained in their correct freezing positions when hand lever 40 is in its freezing position. The final small rearward movement of the front cross wall is caused by gravity until it is stopped by its engagement with the journal pins 41 of lever 40. When in this final or freezing position said front cross wall clears the front edge 51 of its notch 30 by the small clearance 50, for purposes described hereinabove. Preferably each cross wall 25 which underlies hand lever 40 when in its down position has its central upper edge cut away, as best shown at 24 in Fig. 8, to permit lever 40 to lie flush with the upper edges of the cross walls as shown in Fig. 3. This provides a flat surface and facilitates the stacking of the ice trays one upon the other.

In operation, the pan 10 with grid 20 in freezing position therein is filled with water, preferably to the normal water level of about one quarter inch below the upper edges of the pan, and set within a freezing chamber until the contents are hard frozen. To harvest the ice blocks, the ice tray is removed from its freezing chamber and then set upon a table or other surface (or may be held in the hands if so desired) and the hand lever 40 operated to free all or as many of the ice blocks as may be desired at the time, as fully described above. The forwardmost cross wall 25 is directly and positively cammed forward relatively very slowly at first but with a great force until the three endmost ice blocks are loose. The next three ice blocks will not require so great a force to loosen same and the second cross wall can therefore be swung forward more easily than the first. Also all the remaining cross walls are successively progressively easier to swing forward as the pan 10 normally peels from the solid ice cake therein ahead of the cross walls being tilted forward at the time. Hence the cams 45 may readily be given such curvature as to give the highest mechanical advantage when needed most, namely, at the first

loosening of any ice blocks, and still give the desired large total travel to the actuating bars 22 to provide a large angular swing to the last cross wall to be tilted forward.

5 While the embodiment of the present invention as herein disclosed, constitutes a preferred form, it is to be understood that other forms might be adopted.

What is claimed is as follows:

1. A freezing tray having a container pan and a partitioning grid for said pan, said grid comprising: a longitudinal partition wall, a plurality of cross partition walls each having a slot therein thru which a portion of said longitudinal wall extends, said cross walls being tilttable forward relative to said longitudinal wall to loosen them from their bond to the frozen contents of the freezing tray, a hand lever pivoted upon said longitudinal wall adjacent one of said cross walls and having a cam thereon for directly contacting and tilting forward said one cross wall to loosen it from the frozen contents bonded thereto, and mechanical means interconnecting said cross walls and directly actuated by the tilting movement of said one cross wall only after a predetermined movement thereof for tilting forward additional cross walls.

2. A freezing tray having a container pan and a partitioning grid for said pan, said grid comprising: a longitudinal partition wall, a plurality of cross partition walls each having a slot therein thru which a portion of said longitudinal wall extends, said cross walls being tilttable forward relative to said longitudinal wall to loosen them from their bond to the frozen contents of the freezing tray, a hand lever pivoted upon said longitudinal wall adjacent one of said cross walls and having a cam thereon for directly contacting and tilting forward said one cross wall to loosen it from the frozen contents bonded thereto, and an actuating bar extending along said longitudinal wall and arranged to be forced longitudinally along same by the forward tilting movement of said one cross wall for engaging and tilting forward additional cross walls.

3. A freezing tray having a container pan and a partitioning grid for said pan, said grid comprising: a longitudinal partition wall, a plurality of cross partition walls each having a slot therein thru which a portion of said longitudinal wall extends, said cross walls being tilttable forward relative to said longitudinal wall to loosen them from their bond to the frozen contents of the freezing tray, a hand lever pivoted upon said longitudinal wall adjacent one of said cross walls and having a cam thereon for directly contacting and tilting forward said one cross wall to loosen it from the frozen contents bonded thereto, and a longitudinally extending bar so arranged as to be moved forward by the forward tilting movement of said one cross wall only after said one cross wall has been tilted forward a predetermined distance by said cam, said bar engaging the remaining cross walls and serving to tilt them forward to loosen them from the ice contents.

4. A freezing tray having a container pan and a partitioning grid therefor, said grid comprising: two longitudinal partition walls, a plurality of cross partition walls each extending transversely across said two longitudinal walls and mounted thereupon so as to be capable of a forward movement relative thereto, a hand lever pivoted upon both of said longitudinal walls and having cam means for moving forward one of said cross walls to loosen it from the frozen con-

tents bonded thereto, and two actuating bars extending respectively along said two longitudinal walls and arranged to be directly positively forced longitudinally forward by the forward movement of said one cross wall, said bars serving to engage and move the remaining cross walls upon forward longitudinal movement of said bars.

5. A freezing tray having a container pan and a partitioning grid therefor, said grid comprising: two longitudinal partition walls, a plurality of cross partition walls each extending transversely across said two longitudinal walls and mounted thereupon so as to be capable of a forward movement relative thereto, a hand lever pivoted upon both of said longitudinal walls and having cam means for moving forward one of said cross walls to loosen it from the frozen contents bonded thereto, and two actuating bars extending respectively along said two longitudinal walls and arranged to be contacted and forced longitudinally forward by the forward movement of said one cross wall, said bars serving to engage and move the remaining cross walls upon forward longitudinal movement of said bars, said hand lever engaging said two bars to restore same to their initial position upon the return movement of said lever to its initial position.

6. A freezing tray having a container pan and a partitioning grid therefor, said grid comprising: two longitudinal partition walls, a plurality of cross partition walls each extending transversely across said two longitudinal walls and mounted thereupon so as to be capable of a forward movement relative thereto, a lever pivoted upon both of said longitudinal walls closely adjacent one endmost cross wall, said lever having cam means thereon for directly contacting and camming said endmost cross wall forward to loosen it from the frozen contents, two actuating

10

15

20

25

30

bars overlying respectively said two longitudinal walls and arranged to be forced longitudinally relative thereto by a forward movement of said endmost cross wall, said actuating bars having a notched engagement with and serving to move forward some of said cross walls other than said endmost cross wall.

7. A freezing tray having a container pan and a partitioning grid therefor, said grid comprising: two longitudinal partition walls, a plurality of cross partition walls each extending transversely across said two longitudinal walls and mounted thereupon so as to be capable of a forward movement relative thereto, said two longitudinal walls being outwardly inclined toward their lower portions, a hand lever reacting upon said longitudinal walls and directly engaging one of said cross walls for forcing same forward to loosen it from the frozen contents, two longitudinally movable actuating bars for engaging and forcing forward additional cross walls to loosen same from the frozen contents, said actuating bars being mechanically forced forward by said one cross wall and mechanically moved rearwardly by said hand lever upon return movement of said lever to its initial position.
